GRATE

Ellis W. Bullock, Birmingham, Ala., assignor to
Fly Ash Arrestor Corporation, a corporation of
Alabama

Application February 5, 1943, Serial No. 474,795

7 Claims. (Cl. 126—163)

1

This invention relates to furnace grates particularly, to the class employed in furnaces with forced draft and which are subject to intense heat, and has for an object the provision of an article of the character designated which shall be simple of design, extremely sturdy, and provided with especially efficient heat dissipating means.

A further object of my invention is to provide a cast iron grate with sheet steel metal fins joined integrally thereto by casting the grate around the fins.

A further object of my invention is to provide a cast iron grate with integrally corrugated fins cast in same and improved means for supporting the grate in the furnace.

As is well known in the art to which my invention relates grates in forced draft furnaces, especially where a thin fire and spreader stokers are employed, are subject to intense heat and often burn out or break. I have found that by providing a plurality of rows of sheet steel fins extending from end to end of the grates and to which the grates are joined by casting the strength of the grates is materially increased and the heat dissipating effect of the fins is such that the grates have an indefinite life. In addition, air for combustion may be passed over the corrugated fins and heated. By attaching trunnions for the grates to the fins, they are afforded an extremely sturdy support which, being remote from the fire, is not subject to extremes of heat. To afford additional security I provide projections on the sides of the fins where they are cast into the grates.

A grate embodying features of my invention is illustrated in the accompanying drawing forming a part of this application in which:

Fig. 1 is a top plan view;

Fig. 2 is a longitudinal section taken along the line II—II of Fig. 1; and

Fig. 3 is a transverse section taken along the line III—III of Fig. 1.

Referring to the drawing my improved grate comprises a substantially flat cast iron body portion 10 provided with downwardly flaring air openings 11 therethrough. The grate is mounted over the usual wind box 12, so that air under pressure in the wind box passes upwardly through the openings 11 in the grate to support combustion, as is well understood.

Cast integrally with the grate is a plurality of corrugated sheet steel fins 13 which extend from end to end of the grate and are relatively closely spaced, the rows of fins being positioned along

2

the rows of openings 11. In the making of the grate, the fins 13 are joined integrally with the grate, being inserted in the sand mold with the pattern before the cast iron portion 10 is poured, and left protruding from the sand so that the molten cast iron is poured around them. In order to insure a strong juncture between the fins and the cast iron body 10, I may provide projections 14 projecting from the sides of the fins where they extend into the cast iron body 10. These projections may be in the form of small pins which are passed through suitable holes in the fins before the body portion is poured. The fins 13 are preferably made from standard corrugated sheet steel of about one-eighth inch thickness and may extend downwardly under the grate from six to ten inches, depending on the rating of the boiler furnace, or intensity of heat to which the grates may be subjected.

20 In designing the grate I provide a radiating fin surface six times the area of the upper surface of the grates, based on a calculated maximum heat release of 370,000 B. t. u. per hour per square foot of grate area. If a greater heat release is involved the fin surface is increased in direct proportion to the increase in heat release.

It will be seen by reference to Fig. 1 of the drawing that the fins 13, being corrugated, afford not only increased radiating surface, but provide an

30 extremely sturdy beam structure for the support of the grate. The grate is supported from trunnions 16 which are joined to bars 17 which in turn extend entirely across the end of the grate and are welded to the ends of the fins 13. The trunnions 16 rest in bearings 18 which in turn are

35 suitably supported, as at 19, from supports positioned in the wind box 12. By reason of this means of support, even though the cast iron body of the grate be broken, the usefulness of the grate

40 is not gone as it is supported from the fins and not from the body of the grate.

In case the grate is to be employed as a dump grate, I weld a bar 21 across the bottoms of the fins 13 and secure an arm 22 thereto provided

45 with a hole 23 to which suitable linkage (not shown) may be connected for dumping the grate.

The fins 13, in a grate constructed according to my invention, function to add strength to the grate and to protect it from heat. They distribute the heat from hot spots on the grate and thus minimize temperature stresses resulting from hot spots. The added distributing surface of the fins insures that no limited area on the grate shall become overheated. The fins providing many times the radiating surface of the grate

alone, distribute their heat to the air passing up through the grate from the wind box 12 and thus none of the heat to which the grates are subjected is lost, but is used for combustion of the fuel. Also the fins, being made from mild steel and securely joined to and forming a part of the grate, add many times the strength of the body portion 10 alone and provide an excellent means of support for the body portion 10. Even though the body portion be entirely broken, the support for the grate is not impaired and its usefulness not impaired.

From the foregoing it will be apparent that I have devised an improved grate which is simple of design and economical of manufacture and one capable of withstanding rigorous service.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. A cast iron furnace grate comprising a body portion having a plurality of sheet metal fins spaced throughout their lengths from adjacent fins embedded therein on the under side thereof and extending from end to end of the grate, and supporting trunnions welded on to the fins at the ends of the grates.

2. A cast iron furnace grate having a plurality of corrugated sheet metal fins spaced throughout their lengths from adjacent fins integrally joined on the under side thereof extending from end to end of the grate, pins extending through each of the fins where it is joined to the grate at intervals throughout the length thereof for securing the fins in place in the grate, a bar extending across

the grate at each end thereof and welded to the fins, and a trunnion on each of the bars.

3. A furnace grate comprising a plurality of corrugated sheet metal fins spaced throughout their lengths from adjacent fins, a perforate body portion of cast iron cast about one edge of the fins, and means for supporting the grate by the fins.

4. A furnace grate comprising a plurality of corrugated sheet steel fins spaced throughout their length from adjacent fins, a body portion of cast iron cast about one edge of the fins and having uniformly spaced holes between the fins, a bar extending across the grate at each end thereof and welded to the fins only, and a trunnion on each of the bars.

5. In a furnace grate, a plurality of sheet steel fins spaced throughout their length from adjacent fins, a cast iron body cast about one edge of the fins leaving the major portion of the width of said fins extending beyond the body, there being uniformly spaced holes through the body between the fins for the passage of air through the grate, and a trunnion at each end of the grate secured directly to the fins.

6. In a furnace grate, a plurality of sheet metal fins spaced throughout their length from adjacent fins, a cast iron body cast about one edge of the fins leaving the major portion of the width of said fins extending beyond the body, there being uniformly spaced holes through the body between the fins for the passage of air through the grate, a bar extending across the grate at each end thereof and welded to the fins, and a trunnion on each of the bars.

7. A grate, as set forth in claim 6 in which the fins are made of corrugated sheet steel and the holes through the grate body are disposed in sinuous rows paralleling the corrugations of the fins.

ELLIS W. BULLOCK.
